UNITED STATES PATENT OFFICE.

JEAN BORDENAVE, OF PARIS, FRANCE.

MECHANISM FOR MAKING COILS FOR METAL SKELETONS FOR COMPOSITE STRUCTURES.

SPECIFICATION forming part of Letters Patent No. 399,484, dated March 12, 1889.

Application filed September 26, 1887. Serial No. 250,778. (No model.) Patented in France March 10, 1887, No. 182,095; in Italy March 22, 1887, XXI, 21,405, XLII, 357; in England March 23, 1887, No. 4,386, and in Spain March 30, 1887, No. 10,748.

To all whom it may concern:

Be it known that I, JEAN BORDENAVE, a citizen of the French Republic, and a resident of Paris, France, have invented certain 5 Improvements in Mechanism for Making Coils for Metal Skeletons for Composite Structures, (for which patents have been granted in France, No. 182,095, dated March 10, 1887; in England, No. 4,386, dated March 23, 1887; in 10 Spain, No. C. A., 10,748, March 30, 1887, and in Italy No. XXI, 21,405, XLII, 357, dated March 22, 1887,) of which the following is a specification.

My invention relates to the manufacture of 15 iron skeletons for use in building conduits composed of metallic skeletons embedded in cement or concrete.

The metal skeleton of such structures usually consists of bar-iron of plain uniform section, as square or round iron, for the reason 20 that bars with this form of section are more easily bent to the proper curvature for the transverse members or ribs than iron having sections of higher or more complex development, as **T** and **I** iron, for example; but the ordinary iron has not the strength and stiffness in proportion to its cross-section that the latter has. The difficulty in employing **T** and **I** iron as sold by the trade is that in bending 25 it while cold to the curved form required in the structure the metal inside is unduly compressed, while that outside is unduly distended. Thus the bending weakens and forms cracks in the iron and renders it unfit for use 30 in the conduit.

If the iron be heated before the bending, these difficulties will be partially, but not wholly, overcome, and this heating will add very materially to the expense.

The object of my invention is to avoid the 40 above difficulties and to enable iron of highly developed section to be employed, and this I effect by winding the iron of the proper section as it comes from the rolls in the mill (and of course while still very hot and plastic) directly upon a drum-like form, which has the proper contour that is required for the metal skeleton of the structure. The metal is wound upon the form helically or 45 spirally, the "pitch" being precisely that re-

quired in the finished skeleton. The drum-like form on which the metal is wound is provided with a spiral groove to receive the bar and give the proper pitch to the spiral, and said drum is splined on its shaft in order that 55 it may move endwise or longitudinally thereon and adapt itself to the rolls as the winding proceeds.

In order that my invention may be the better understood, I will describe it with reference to the accompanying drawings, wherein—

Figure 1 is a sectional elevation, and Fig. 2 is a plan, of the mechanism for rolling and winding on the bar which forms the spiral of 65 the skeleton. Fig. 3 is a view illustrating the manner of bundling the spiral coils for convenience of transportation. Fig. 4 is a view of the bundled coil. Fig. 5 is a side view, and Fig. 6 an end view, of the mechanism for 70 building up the skeleton.

Referring to Figs. 1 and 2, as the bar *a* of iron to form the spiral issues from the rolls *A* it is wound upon a drum, *B*, provided with a helical groove, *b*, in its surface to receive the bar. The grooves or "lands" between the spirals of the groove *b* are of the exact width that is required for the spaces between the spirals of the skeleton. The automatic endwise movement of the drum *B* required to 75 adapt it to receive the bar properly as it comes from the rolls may be effected by means of a fixed stud, *c*, which engages the spiral groove *b* in the drum. Thus the drum is driven endwise by its own rotation like a screw. The 80 coil thus formed may be compactly bundled for transportation by compressing the spirals together, as shown in Fig. 3, and tying them together with wires *e e*, for example. Fig. 4 shows the bundle or package thus tied up. 85

In the preceding description I have illustrated the winding of a cylindrical coil destined to form a pipe. In order to build up the skeleton, the coil *a a* is slipped on a drum or mandrel, *C*, the ligatures *e e* removed, and the 90 spirals properly distanced or spaced as they were when the coil was originally wound. The longitudinal bars or rods *f f* are slipped into longitudinal flutes or grooves formed in the periphery of the drum *C* and properly 95

spaced. These longitudinal bars or rods and the spirals are then tied or ligatured where they cross each other by wires *g g*, and this completes the section of the skeleton. The 5 skeleton thus constructed may be laid or set and the cement or concrete applied in any manner. This application of the cement forms no part of my present invention.

The drum *B* need not be cylindrical. It 10 may have any sectional contour suited to the form of the conduit to be built.

Having thus described my invention, I 15 claim—

1. As a means of forming the metallic coil 20 destined to form the skeleton of a cement pipe, the combination, with the rolls for rolling the metal bar, of a drum having the proper sectional contour rotatively mounted adjacent to said rolls, said drum having a spiral

peripheral groove to receive the bar and being capable of endwise movement, substantially as set forth.

2. The combination, with the rolls *A* for rolling the flanged bar, of the drum *B*, rotatively mounted adjacent to the rolls and having a peripheral spiral groove, *b*, to receive the bar from the rolls, said drum being free to move longitudinally, and a fixed stud, as *c*, engaging the spiral groove in the drum and serving to feed the latter endwise, substantially as set forth.

In witness whereof I have hereunto signed my name in the presence of two subscribing witnesses.

JEAN BORDENAVE.
